GAMMA ALUMINA PROMOTED PARAFFIN ALKYLATION PROCESS

George R. Gilbert, Elizabeth, John E. McCormick, Roselle Park, and Alan Schriesheim, Fords, N.J., assignors to Esso Research and Engineering Company, a corporation of Delaware

Filed Dec. 1, 1958, Ser. No. 777,313

6 Claims. (Cl. 260—683.53)

This invention concerns a process involving simultaneous cracking, isomerization and alkylation reactions wherein, as a net result, certain paraffin hydrocarbons are alkylated with other paraffin hydrocarbons. Accordingly, the process can be termed a paraffin alkylation process. More specifically, the invention relates to a process wherein a butane or a pentane is reacted with a paraffin hydrocarbon of from 6 to 18 carbon atoms in the presence of aluminum bromide and a promoter support comprising gamma alumina, under conditions that result in high yields of branched chain paraffin hydrocarbons of from 5 to 7 carbon atoms.

Petroleum refiners are continuously faced with the problem of supplying better and greater quantities of high octane rating motor fuels to meet the requirements of modern high compression internal combustion engines employed in the automotive industry. Heretofore, the supply of high octane rating gasoline components has been augmented principally by polymerization and alkylation processes using C_3 and C_4 petroleum fractions as starting materials. These processes have a number of disadvantages in that they require several separate operations and necessitate the use of olefin hydrocarbons which are usually in relatively limited supply.

It has now been found that, by the use of a promoted aluminum bromide catalyst, butanes and/or pentanes can be reacted directly with higher paraffin hydrocarbons to give good yields of C_5 to C_7 branched chain hydrocarbons of high octane rating, provided certain specific conditions are employed. It has previously been proposed to conduct reactions of this type but yields have been low, reaction rates have been uneconomic and satisfactory product distribution has not been obtained.

In accordance with the present invention, a paraffin hydrocarbon of from 6 to 18 carbon atoms is reacted with a large excess of a butane or a pentane, preferably isobutane, employing as a catalyst $AlBr_3$ supported on or associated with gamma alumina, at temperatures in the range of from about 30° to about 140° F. and at pressures sufficient to keep the reacting hydrocarbons in the liquid phase. The products of the reaction are saturated branched chain paraffin hydrocarbons predominantly in the C_5 to C_7 range. The preferred temperature range is from about 50° to about 120° F.

The nature and objects of this invention and the manner in which the invention can be practiced will be more readily understood when reference is made to the accompanying drawings in which the single figure is a schematic flow plan of one process for practicing the invention.

The process will be described with particular reference

2

to the use of isobutane as the lighter component. Referring to the drawing in detail, a suitable butane feed stream containing at least initially a major proportion of isobutane is obtained by means of line 11 from a suitable source. A portion of the stream is conducted via line 11a through an aluminum bromide pick-up vessel 12 to dissolve aluminum bromide in a portion of the stream that is conducted to the reaction zone. The remainder of the feed stream is combined with the effluent leaving the pick-up vessel via line 13 and is conducted into a reaction zone 15. The latter zone contains one or more beds of gamma alumina saturated with aluminum bromide.

A stream of a higher paraffin hydrocarbon, as for example, heptane, octane, dodecane or cetane, or of mixtures containing the higher paraffins, is conducted into the reaction zone by means of line 16. Preferably the stream enters the reaction zone at a plurality of spaced points, 16a, 16b, etc., so as to insure as high a ratio as possible of isobutane to higher paraffin at any particular point in the reaction zone.

The reaction product leaves the reaction zone through line 18 and is conducted into an initial separation zone 20 wherein light materials, including unreacted isobutane and normal butane, are removed overhead and recycled to the reaction zone by means of line 21. Hydrogen bromide, which is preferably present, will also be recycled via line 21. The heavier material, including C_5 hydrocarbons and higher, is conducted by means of line 22 into a product separation zone 24 wherein C_5 to C_7 hydrocarbons are removed overhead by means of line 25 while heavier material comprising C_8 hydrocarbons and higher as well as any aluminum bromide that has been removed from the reaction zone is recycled to the reaction zone by means of line 26. If desired, conditions can be adjusted in separation zone 24 to include normal heptane in the heavier material recycled through line 26, while including the C_7 branched chain isomers in overhead line 25.

In place of isobutane the feed in line 11 may comprise normal butane, in which case no higher hydrocarbon feed stock will be sent initially to the reaction zone but the butane will be recycled through line 18, zone 20 and line 21 until a considerable amount of the butane has been isomerized to isobutane. The process may then continue in the manner already described, the recycle isobutane being sufficient to make the desired reaction proceed while the fresh butane feed becomes isomerized to isobutane in the reactor.

A number of factors in the process of the present invention are critical to its operation in order that proper distribution of the products may be obtained. For example, at temperatures above about 140° F. considerable cracking occurs and the principal products are propane and lighter materials. Also it has been established that aluminum bromide alone or even in the presence of conventional hydrogen halide promoters such as hydrogen bromide, in the absence of the support, is very much less active than the catalyst system of the present invention. Furthermore in order for the reaction to proceed satisfactorily it is necessary that sufficient aluminum bromide be present not only to saturate the support under the reaction conditions employed but also to leave at least a small amount dissolved in the reacting hydrocarbons.

A mixed catalyst in which a portion of the aluminum

bromide is replaced with aluminum chloride may be used provided that at least some aluminum bromide is present in the reacting hydrocarbons over and above that which is adsorbed on the support.

Although the reaction may proceed in the absence of hydrogen bromide promoter it is preferred that it be used as an auxiliary promoter in addition to the gamma alumina. A range of from about 0.1 to 8% or more of HBr by weight based on total feed may be used, while from about 1% to about 5% is preferred. The hydrogen bromide is introduced into the reaction zone by means of line 17 and is recycled to the reaction zone along with unreacted butanes by means of line 21.

Although the process as described in conjunction with the drawing contemplates downflow of the stream through the catalyst bed, which is preferred, upflow can also be used. Also in place of a fixed bed process, a moving bed of catalyst could be used. Alternatively, a slurry type of operation could be employed wherein a suspension of catalyst is maintained in the reacting hydrocarbons, the slurry being stirred in the reactor with suitable mechanical stirring means or recirculated through the reactor by pumping means. Where slurry operation is used, the slurry is removed from the reactor at the end of the reaction period, in the case of batch operation, or as a fraction of the circulating stream in the case of continuous operation, and sent to suitable separation equipment to separate the catalyst from the hydrocarbons. The separation equipment may comprise a simple settling tank, a centrifuge, or a filter, for example, or suitable combinations of such means.

It is preferred that the minimum mol ratio of isobutane and/or isopentane to higher paraffin be about 3 to 1 but should preferably be no higher than about 12 to 1. If sufficient iso-C₄ is not present in the reaction zone to effect alkylation of the materials obtained when a higher paraffin or other higher product of the reaction is cracked by the catalyst, catalyst sludging will result. The feed stock must be essentially free of aromatic hydrocarbons and not more than about 0.02% of such material should be present. An added advantage of the catalysts of the present invention is that naphthene hydrocarbons may be tolerated in the feed stock up to about 20 volume percent. With increased naphthene content the reaction severity must be increased somewhat as compared to a reaction in the absence of naphthenes. This may be accomplished by raising the temperature and/or lowering the feed rate, for example.

Feed rates may vary from about 0.3 to about 2 v./hr./v. (liquid volume of total feed per hour per volume of total catalyst plus support) the higher feed rates being preferred when little or no naphthenes are present.

To remove aromatics from the feed stock conventional techniques may be employed such as solvent extraction, hydrogenation, acid treating and the like, as well as treatment with selective adsorbents such as molecular sieve zeolites. It is not necessary that the higher hydrocarbons used be individual hydrocarbons such as heptane or octane or cetane, for example, but mixtures may be used, such as a petroleum fraction containing paraffinic hydrocarbons in the range of 6 to 18 carbon atoms. Although, as stated, hexane is one of the higher hydrocarbons that may be used, it is preferred to employ heptane or higher. Essentially the same product distribution is obtained with hexane as with heptane but the reaction rate is lower by a factor of about 3. Other sources of the higher paraffin hydrocarbons for the reaction include light virgin naphthas, and paraffin raffinates from the extraction of hydroformed petroleum fractions.

At the start of the process the gamma alumina may be saturated with aluminum bromide and then placed in the reaction zone, or, alternatively, the gamma alumina alone may be placed in the reaction zone and then saturated with aluminum bromide carried in with a portion of the feed. Another method of preparation is to mix

the aluminum halide with the support and to heat the mixture to effect impregnation. If desired, loosely held aluminum halide may be removed from the catalyst mass by heating the mass and passing through it a gas such as carbon dioxide, methane, hydrogen or nitrogen.

Alternatively the support may be impregnated by dissolving the aluminum halide in a suitable solvent such as ethylene dichloride or dioxane, for example, and the porous carrier impregnated with this solution, followed by heating to remove the solvent and loosely held aluminum halide. Still another alternative is to employ a powdered support or promoter, mix the aluminum halide with it, and compress the mixture into pellets.

The following examples serve to illustrate the practice of the present invention.

EXAMPLE 1

Comparative tests were made with various catalyst systems as shown in Table I. In each instance a mixture of 160 cc. (90.5 grams) of isobutane and 40 cc. (27.5 grams) of a normal heptane feed, which consisted of 95% of normal heptane and 5% of methyl cyclohexane, was stirred for 3 hours at 72° F. with one of the catalyst systems mentioned above. At the end of each run 20 the yield of products was determined as shown in Table I. Aluminum bromide alone or even in the presence of hydrogen bromide was not effective in producing the desired reaction, as in each instance the major proportion of the product consisted of C₇ hydrocarbon isomers. 25 On the other hand, gamma alumina was a very effective promoter for the aluminum bromide catalyst and gave considerable yields of C₅ and C₆ isomers. Still greater activity was obtained when a small proportion of hydrogen bromide was employed in addition to the gamma alumina.

The gamma alumina used in these tests was prepared as follows. Aluminum alcoholate was prepared by reaction of aluminum metal with a 3 to 1 volume ratio mixture of mixed amyl alcohols and heavy virgin naphtha, using a trace of mercuric chloride to promote the reaction. The ratio of reactants was about 3 pounds of aluminum per 7 gallons of the alcohol-naphtha mixture. The aluminum content of resulting aluminum alcoholate solution was about 94 to 97 grams of alumina per liter. 40 The aluminum alcoholate was pump-mixed at room temperature with a diluent (2.2 volumes of alcoholate per volume of diluent) consisting of mixed amyl alcohols, heavy naphtha and acetic acid in a volumetric ratio of 15 to 15 to 1. This stream was then hydrolyzed with 45 6.8 volumes of water at room temperature in a second mixing pump. The mixed product was pumped through a heat exchanger held at 160° F. outlet temperature. From the heat exchanger the product went to a separator held at 160° F. The alcohol and solvent layer were continuously withdrawn from the top of the separator while the aqueous layer flowed continuously into a steam jacketed stainless steel sol cooking unit and heated to boiling for 4 hours. During the heating, alcohol and solvent remaining in the slurry were taken overhead 50 from the cooking unit, together with water. The alcohol-solvent mixture and water were separated and measured, and the water returned to hold constant volume.

Five 100-gallon batches of alumina sol were prepared in this manner and mixed together. Analysis after mixing indicated an alumina content of 3.1 percent. The entire mixture was spray dried in a tower in a rising stream of flue gas having an entering temperature of 590-625° F. and an exit temperature of 220-230° F., the entering stream of alumina sol being preheated to 55 175° F. The 500 gallons of alumina sol were dried in seven hours to produce 161 pounds of spray dried product containing 32% volatile matter. About 570 pounds of water were evaporated per hour during this drying operation. The product obtained was gamma alumina. 60 Before using it as a support or promoter for aluminum

bromide in the tests described herein it was calcined at 1100° F. for 4 hours.

Total C ₇	98.8	95.6	32.7	24.9

EXAMPLE 2

In a manner similar to that employed in Example 1, comparative tests were made with gamma alumina, eta alumina and calcined bauxite. Each of these materials was employed with aluminum bromide in 2 different ratios of catalyst to support. The same reaction temperature and time and the same hydrocarbon feed was employed as in Example 1. The gamma alumina was prepared in the manner previously described. The eta alumina and the bauxite were obtained from commercial sources. In each case the support used was calcined for 4 hours at 1100° F. before use. It will be seen from the data presented in Table II that gamma alumina was much more active than either of the other two supports in converting the isobutane and normal heptane into C₅ and C₇ paraffin hydrocarbon isomers.

Gamma alumina prepared from sodium aluminate and obtained commercially showed about the same activity as that reported in Table II. In a similar test, the commercial gamma alumina in the ratio of 47.2 grams to 23.6 grams of AlBr₃ gave, in the 3-hour test, 42.4% C₅ hydrocarbons, 26.0% C₆ hydrocarbons and 30.7% C₇ hydrocarbons.

Table II

Promoter	Gamma Alumina		Calcined Bauxite		Eta Alumina	
Promoter, grams	47.2	47.2	47.2	47.2	47.2	47.2
AlBr ₃ , grams	23.6	35.3	28.6	37.8	23.6	35.4
Analysis of C ₅ +						
iso-C ₅	37.4	45.8	22.6	21.7	6.2	8.2

C ₈ +	1.7	1.3	0	1.9	0.2	0.3

EXAMPLE 3

Even greater activity for the desired alkylation reaction was obtained, as measured by conversion of C₇ hydrocarbons to C₅ and C₆ hydrocarbons, by using larger ratios of aluminum bromide to gamma alumina. The test results are shown in Table III. Again the same reaction temperature and time and the same hydrocarbon

feed were employed as in Example 1. The gamma alumina was prepared as described above.

Table III

5	Gamma Alumina, grams	47.2	47.2	47.2

	n-C ₆	1.3	1.6	1.5
20	Total C ₆	29.9	31.0	29.6
	iso-C ₇	12.1	10.5	7.8
	n-C ₇	0.3	0.6	0.4
25	Total C ₇	12.4	11.1	8.2
	C ₈ +	0.4	1.8	1.2

It has been established in other studies that in order for the reaction to proceed satisfactorily it is necessary to have present in the reaction zone sufficient aluminum bromide so that not only will the total adsorption capacity of the gamma alumina be satisfied but some aluminum bromide will be present in solution in the reacting hydrocarbons. To make sure that such a condition will exist in continuous operation, the gamma alumina in the reaction zone should be saturated with aluminum bromide, and sufficient aluminum bromide should be dissolved in at least one of the entering streams of reacting hydrocarbons so that a minimum of 0.1 weight percent of aluminum bromide based on feed is sent to the reaction zone.

35 Although in the illustrative examples given, the higher paraffin hydrocarbon reactant comprised heptane, other studies have shown that with hydrocarbons of greater molecular weight such as octane, cetane, or octadecane, the product distribution is essentially the same as with heptane.

40 Certain modifications of the process outlined herein-before will occur to those skilled in the art. Such modifications are contemplated within the scope of the present invention. For example, if the yield of C₅ hydrocarbons is larger in proportion to the C₆ hydrocarbons than is desired, the product may be distilled to separate a C₅ cut which may then be used in a conventional alkylation step with an olefin such as ethylene, propylene or a butene, employing the usual alkylation catalysts such as sulfuric acid, phosphoric acid, hydrogen fluoride, or an aluminum halide. Alternatively, the C₅ cut can be sent to a second reaction zone of the type herein described for reaction with higher normal paraffin hydrocarbons.

45 55 It is to be understood that this invention is not to be limited to the specific embodiments and examples herein described and presented but that its scope is to be determined solely by the claims appended hereto.

50 59 What is claimed is:

60 1. A process for the preparation of high octane naphtha components consisting largely of branched chain paraffin hydrocarbons of 5 to 7 carbon atoms which comprises reacting a minor proportion of a straight chain paraffin hydrocarbon of from 6 to 18 carbon atoms with a major proportion of a lighter hydrocarbon selected from the group consisting of butanes and pentanes, at temperatures no higher than about 140° F., in a reaction zone in the presence of a catalyst comprising aluminum bromide and gamma alumina and maintaining 65 in the reaction zone sufficient aluminum bromide to furnish aluminum bromide in solution in the reacting hydrocarbons in addition to the quantity required to satisfy the total adsorption capacity of the gamma alumina.

70 65 75 2. Process as defined by claim 1 wherein from about 0.1 to about 8 percent of hydrogen bromide, based on

the reacting hydrocarbons, is present in the reaction zone.

3. Process as defined by claim 1 wherein the mol ratio of said lighter hydrocarbon selected from the group consisting of butanes and pentanes to said hydrocarbon of from 6 to 18 carbon atoms in the reaction zone is in the range of from about 3 to 1 to about 12 to 1.

4. Process as defined by claim 1 wherein naphthenic hydrocarbons are present in said reaction zone.

5. Process as defined by claim 1 wherein the temperature of the reaction is in the range of about 50° to about 120° F.

6. Process as defined by claim 1 wherein reacting hydrocarbons are continuously conducted into said reaction zone and reaction products are continuously re-

5 moved from said reaction zone and wherein sufficient aluminum bromide is dissolved in at least one entering stream of reacting hydrocarbons so that at least 0.1 weight percent of aluminum bromide is continuously added to said reaction zone, based on the total feed of hydrocarbons.
